UNITED STATES PATENT OFFICE.

WILLIAM GRIKSCHET, OF DETROIT, MICHIGAN.

CARBURETOR.

Application filed November 27, 1922. Serial No. 603,637.

The invention relates to carburetors and has, for its main object, the provision of a carburetor having a nozzle communicating with the carburetor outlet and extending into the float chamber, and means within the float chamber and dependent upon the suction effect of the nozzle to effect the flow of liquid fuel into the float chamber from a lower level. Another object is to provide a carburetor which can be readily adjusted to operate as a gravity feed type of carburetor in which the liquid fuel flows into the float chamber from a higher level. Further objects of the invention reside in the novel features of construction and combinations and arrangements of parts as more fully hereinafter set forth.

In the drawings:

Figures 1 and 2 are transverse cross sections through a carburetor embodying my invention taken on the lines 1—1 and 2—2 respectively;

Figure 3 is a cross section on the line 3—3 of Figure 1.

1 is the outlet in the carburetor body and 2 the primary air inlet communicating therewith, both the outlet and inlet extending laterally with the inlet slightly lower than the outlet. 3 is the throttle valve in the outlet, and 4 the choke valve in the inlet. 5 is a tube depending into the float chamber 6 located below the outlet and inlet, and 7 is an upper tube telescopically engaging in the enlarged upper portion 8 of the tube 5. These two tubes form the fuel discharge conduit of the carburetor, the lower end of the tube 5 being open and the rear portion of the wall of the tube 7 having longitudinally spaced openings 9 for placing the interior of the tube in communication with the outlet 1. 10 is a fuel valve extending axially through the tubes 5 and 7 and also through the opening 11 in the bottom of the cup 12.

13 is a vertically reciprocable plunger within the cylinder 14 formed in the carburetor body and so located that the plunger is adapted to variably restrict the communication between the outlet and the primary inlet. The position of this plunger is determined by the pressure within the outlet in rear of the throttle valve and is dependent upon the difference in the pressures below and above the plunger, the pressure therebelow being the same as the pressure in the primary air inlet, while the pressure

thereabove is the same as the pressure in the outlet below the throttle valve. This latter pressure is secured by placing the interior of the cylinder above the plunger in communication with the outlet below the throttle valve through the restricted equalizing passage 15. The lowermost position of the plunger is determined by means of the coil spring 16 surrounding the guide rod 17 slidably engaging the bore 18 in the plunger. The lower end of the plunger with the exception of the rear portion is preferably formed at an angle, and the rear lower end portion is spaced above the upper end of the tube 5 when the plunger is in its lowermost position. Also, the upper tube 7 has an opening 9 in communication with the outlet when the plunger is in its lowermost position.

The fuel valve 10 and also the upper tube 7 are secured to the plunger 13 to be raised and lowered therewith, the arrangement being such that as the plunger rises, the effective area of the opening 11 increases as does also the effective areas of the discharge openings 9. Furthermore, the effective area of the passage for the primary air entering the outlet increases.

To secure the flow of liquid fuel into the float chamber from a lower level, and in the present instance from the liquid fuel supply air-vented tank 19 which is located below the carburetor, the cup 12 within the float chamber has an open upper end located above the level of the liquid fuel within the float chamber, and the bottom of this cup which is preferably rounded, is located at a slight distance from the lower end of the tube 5. This cup is mounted upon the hollow support 20 which has the lateral openings 21 in its wall for placing the interior of the float chamber in communication with the opening 11 in the bottom of the cup. There is also the air vent opening 22 communicating with the vertical passage 23, which latter communicates with the interior of the float chamber through the lateral opening 24 near its bottom. The passage 23 is formed in a vertically extending boss 25 at one side of the float chamber, and the air vent opening 22 is located above the level of the liquid fuel in the float chamber. 26 is a suitable float connected to the control valve 27 for maintaining a constant level in the float chamber.

In operation, the suction effect in the out-

let 1 below the throttle valve 3 which is produced by the suction producing means of the carburetor is transmitted through the exposed opening or openings 9 in the upper tube 7, thereby drawing the liquid fuel from the float chamber through the openings 21 and 11 into the fuel discharge conduit, since air is admitted into the float chamber through the opening 22, vertical passage 23, 10 and opening 24. Also, the suction effect is transferred to the space within the float chamber above the level of the liquid fuel therewithin by means of the cup 12 which has an open upper end, this suction being 15 sufficient to draw the liquid fuel from the supply tank 19 into the float chamber through the intermediate pipe connection, the amount of air entering the float chamber through the air vent opening 22 being restricted sufficiently to permit of the necessary suction. It has been found desirable in practice to space the portion of the bottom of the cup 12 which is directly in line with the wall of the tube 5 approximately 20 $\frac{1}{2}$ of an inch below the lower end of this wall, and to make the opening 24 approximately $\frac{1}{2}$ of an inch in diameter.

The pressure in the outlet in rear of the throttle valve also controls the position of 25 the plunger with the attached fuel valve and upper tube.

The cup may be vertically raised to bring

its bottom into contact with the lower end of the tube 5, at which time the carburetor is adapted to function as a gravity feed type of carburetor in which the liquid fuel flows into the float chamber from a higher level. This vertical adjustment of the cup may be secured by suitable means and as shown in the present instance is accomplished by means of the rock arm 28 engaging in a groove 29 in the lower end of the support 20, the rock arm being mounted upon the shaft 30 which is actuated by the lever 31 which may be actuated from a remote point by a suitable connection 32.

What I claim as my invention is:

In a carburetor, a mixing chamber, a constant level chamber, a tube fixed in the wall of said mixing chamber and extending into said constant level chamber, an adjustable cup in said constant level chamber surrounding said tube, said tube being open to the atmosphere and having a valve seat in its bottom, and a needle valve responsive to the depression in said mixing chamber extending through said tube to cooperate with said valve seat, so that adjustment of said cup simultaneously varies the free opening of the fuel passage and the air passage between the end of said tube and the bottom of said cup.

In testimony whereof I affix my signature.

WILLIAM GRIKSCHET.
